(57) **CLAIM**

The ornamental design for a stalk mounted automated manual shifter, as shown and described.

DESCRIPTION

FIG. 1 is a front-right-top perspective view of the first embodiment of a stalk mounted automated manual shifter, showing our new design;

FIG. 2 is front elevational view thereof;

FIG. 3 is rear elevational view thereof;

FIG. 4 is a top plan view thereof;

FIG. 5 is a bottom plan view thereof;

FIG. 6 is right side elevational view thereof;

FIG. 7 is left elevational view thereof;

FIG. 8 is a front-right-top perspective view of the second embodiment of a stalk mounted automated manual shifter, showing our new design;

FIG. 9 is front elevational view thereof;

FIG. 10 is rear elevational view thereof;

FIG. 11 is a top plan view thereof;

FIG. 12 is a bottom plan view thereof;

FIG. 13 is right side elevational view thereof; and,

FIG. 14 is left elevational view thereof.

The dashed broken lines in the drawings show portions of the coordinate input device that form no part of the claimed design. The dot-dot-dash broken lines in the drawings define the bounds of the claimed design and form no part thereof.

1 Claim, 12 Drawing Sheets
